(57) **CLAIM**

The ornamental design for a horticulture grow light, as shown and described.

DESCRIPTION

FIG. 1 is a perspective view of a horticulture grow light, as viewed from above, showing my new design;

FIG. 2 is a perspective view of the horticulture grow light shown in FIG. 1, as viewed from below;

FIG. 3 is a left side elevation view of the horticulture grow light shown in FIG. 1;

FIG. 4 is a right side elevation view of the horticulture grow light shown in FIG. 1;

FIG. 5 is a front elevation view of the horticulture grow light shown in FIG. 1;

FIG. 6 is a rear elevation view of the horticulture grow light shown in FIG. 1;

FIG. 7 is a top plan view of the horticulture grow light shown in FIG. 1; and,

FIG. 8 is a bottom plan view of the horticulture grow light shown in FIG. 1.

The broken lines immediately adjacent to the shaded areas depict the bounds of the claimed design, while all other broken lines are directed to environment. In addition, the unshaded surfaces that directly adjoin the claimed solid line edges form no part of the claimed design. None of the broken lines form a part of the claimed design.
